ATTORNEY

UNITED STATES PATENT OFFICE.

CHARLES W. MUCHALL, OF WIESBADEN, GERMANY, ASSIGNOR TO WILLIAM E. BRACKLO, OF NEW YORK, N. Y.

GAS-LAMP.

SPECIFICATION forming part of Letters Patent No. 252,692, dated January 24, 1882.

Application filed December 5, 1881. (No model.) Patented in Germany April 20, 1880.

To all whom it may concern:

Be it known that I, CHARLES WILLIAM MUCHALL, of Wiesbaden, in the German Empire, have invented certain new and useful Improvements in Gas-Lamps, of which the following is a specification.

This invention has reference to improvements in gas-lamps of that class which are constructed on the so-called "regenerative" principle—that is to say, in which the air required for combustion is not conducted directly to the burner from below, as usual, but drawn in through a space formed between an interior and exterior chimney, and thence supplied in a heated-up state to the flame, so as to produce a more perfect and economical combustion of the gas.

The invention consists in a gas-lamp having an interior cylinder in connection with an exterior cylinder, which is supported on a separate closed cup below the burner and held centrally to the interior cylinder by means of steadyng-springs applied to the gallery of the burner. The exterior cylinder is arranged with an outwardly-bulging reflector above the lower portion, which reflector is made in one piece with the lower portion of the exterior cylinder and connected at the upper contracted part by a retaining-gallery with the interior chimney. The switch is regulated by a lever extended below the supporting-cup of the outer chimney.

In the accompanying drawings, Figure 1 represents a vertical central section of my improved gas-lamp; Fig. 2, a side view of the same; and Fig. 3, a horizontal section of the same on line *xx*, Fig. 1.

Similar letters of reference indicate corresponding parts.

In the drawings represents the exterior cylinder of my improved gas lamp, and *C* the interior cylinder, which latter is supported in the usual manner on the gallery of an Argand burner, *D'*. The exterior cylinder, *A*, is extended below the gallery of the interior cylinder, *C*, and supported on a shoulder of a glass or other cup, *D*, which is secured permanently to the gas-supply tube below the burner, as shown clearly in Fig. 1. The outer cylinder, *A*, can be readily removed for cleaning from the supporting-cup *D*. The exterior cylinder, *A*, is

retained in position centrally to the interior cylinder, *C*, by means of steadyng-springs *a*, which extend downward from the gallery of the burner *D'*, as shown clearly in the drawings.

The upper part of the exterior cylinder, *A*, is bulged outwardly, forming a reflector, *B*, which is made integral with the cylinder *A*. This reflector *B* is contracted at its upper end and retained concentrically with the inner cylinder, *C*, by a detachable gallery, *b*. The upper part of the reflector *B* may be made either of ground or opaque glass, so that the rays of the light coming from the flame are reflected downward without requiring a separate reflector or shade, as customary in the Argand lamps of this class.

The lower part of the cylinder *A* may be made either of plain cylindrical shape or with annular parallel horizontal grooves and ribs, as in Fig. 1; or it may be bulged out in the shape of a globe, as shown in dotted lines in Fig. 1, and in full lines in Fig. 2; or it may be made in any other form, as desired. The lowermost part, *a'*, of the outer cylinder, *A*, is made of cylindrical shape and somewhat contracted, it being supported on an annular shoulder, *a²*, of the cup *D*, and retained by an annular guide-rim, *a³*, of the same, as shown in Fig. 1. The centering-springs *a* press from the inside upon the contracted lowermost part, *a'*, of the cylinder *A*, so that the same is thereby rigidly held in position concentric to the inner cylinder, *C*.

For the purpose of regulating the switch *E* of the burner *D'*, which in this case could not be taken hold of by the hand, a crank-lever, *E'*, is connected at its upper end to the eye of the switch-arm and extended downward along the gas-supply tube, the lever being provided with a handle below the supporting-cup *D*. The crank-lever *E'* is retained in fixed rings of the gas-tube, so that the lever *E'*, and thereby the switch *E*, can be readily turned from the outside.

The air required for combustion is drawn in from the outside through the annular space between the interior cylinder, *C*, and the upper end of the exterior cylinder, *A*, and is first warmed up in the bulged-out space at the interior of the reflector, being then drawn downward

in the space between the lower part of the exterior cylinder, A, and the interior cylinder, C, and finally conducted to the burner, the air being thus highly heated up on its way to the burner. The illuminating-gas is also heated up to some extent in the short piece of tube inside of the supporting-cup D. The supply of highly-heated air to the flame of the burner produces the more perfect combustion of the gas, and increases, consequently, the illuminating power of the flame.

Having thus described my invention, I claim as new and desire to secure by Letters Patent—

1. In a gas-lamp, the combination, with an interior cylinder supported on the gallery of the burner, of an exterior cylinder provided with an enlarged conical reflector at the upper part, of a fixed supporting-cup, and of devices whereby the outer cylinder is retained concentrically to the inner cylinder both at its upper and lower ends, substantially as set forth.

2. The combination, with an interior cylinder,

C, an exterior cylinder, A, having an enlarged conical reflector, B, at the upper part and a cylindrical contracted portion, a', at the lower part thereof, of a fixed supporting-cup, D, having an annular shoulder, a², and guide-rim, a³, of centering-springs a binding upon the lower contracted portion, a', of the outer cylinder, and of a detachable gallery, b, retaining the upper end of the same, substantially as set forth.

3. The combination, in a gas-lamp, with the switch of the burner, of a crank-lever, E', applied to the switch and extended below the closed cup D, so as to operate the switch from the outside, substantially as described.

In testimony that I claim the foregoing as my invention I have signed my name, in presence of two witnesses, this 9th day of April, 1881.

CHARLES WILLIAM MUCHALL.
